UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

RAILWAY-CAR UNDERFRAME.

1,164,060.

Specification of Letters Patent. Patented Dec. 14, 1915.

Application filed August 4, 1915. Serial No. 43,603.

To all whom it may concern:

Be it known that I, PAUL M. BEARD, residing at St. Louis, Missouri, and being a citizen of the United States, have invented 5 certain new and useful Improvements in Railway-Car Underframes, of which the following is a full, clear, and exact description, such as will enable others skilled in the art to which it appertains to make and use 10 the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is a plan view 20 of a part of a center sill construction adjacent the bolster, part of the figure being in section along line 1—1 of Fig. 2. Fig. 1^a is a detached diagrammatic view showing a part 25 of a rectangular plate, such as is employed in the fabrication of the web of a sill, of fish-belly form, like that shown in the drawings. Fig. 2 is a side elevational view of 30 the structure shown in Fig. 1. Fig. 3 indicates a transverse sectional view, the section being taken on line 3—3 of Fig. 2. Fig. 35 4 is a diagrammatic plan view of one half of a car underframe, of the type to which the sills of the present application may be applied. Fig. 5 is a side elevational view of a modified sill in which the web and its re- 40 inforcement, hereinafter referred to, extend to the end sill, the end sill not being shown. Figs. 6, 7 and 8 are sectional views, the sections being taken respectively on lines 6—6; 45 7—7 and 8—8 of Fig. 5.

Referring to the parts 1 indicates the 50 center sill web having a flange 2 at the top, which flange is shown as integral with the web in Figs. 1, 2 and 3, and comprises a separately formed attached angle in Figs. 5, 6 and 7. To the top flange 2 is secured the usual cover plate 3.

4 and 5 indicate respectively bottom chord angles, secured to the inner and outer faces 55 of the webs 1 of the center sills, and said chord angles terminate intermediate the bolsters, and between the bolsters and the end sills respectively, it being understood of course that there is employed in the underframe two bolsters, one near either end of the car.

7 indicates a cross beam or cross bearer passing transversely through the web 1 of the center sill, and being connected thereto by castings 8 provided with integral flanges 8^a, conforming in general to the contour of the flanged side of the cross beam, and being also connected to the stiffening members 9, which in the present instance are of angle formation in cross section. 60

10 is a flanged reinforced casting, which serves as a connecting member between the bolsters and the center sills, said casting being provided with connected passages of the contour of the bolster B projected therethrough, as best shown in Figs. 1 and 2. 65

The center sill web in the present invention is formed from a rectangular plate of metal, the end portion of which plate is shown in Fig. 1^a. The accepted method of forming the web of a fish-belly sill from such a plate, is by making two cuts at each end, one cut extending parallel with the top of the plate, as shown along the line a of Fig. 1^a, and one cut extending diagonally from the inner end of said first cut a to the bottom of the plate along the line b in said Fig. 1^a. These cuts shape the web plate as shown in Fig. 2, and sever from said web plate a piece of metal of the shape indicated at 11 in said Fig. 1^a. 70

Ordinarily the piece of metal 11 would not be employed as a part of a center sill, but would be thrown into the "scrap" to be utilized as far as might be found conveniently practicable in the manufacture of small parts such as plates and gussets to be used in various parts of the car. Such practice results in a considerable waste of material, and at best the parts cut from such scrap are as costly as if cut from plates of a 75

larger size. In the present construction the piece 11, severed from the web, as above indicated, is used as shown in the drawings to reinforce the center sill web at and adjacent the bolster. In the sill produced in accordance with the present invention, the web section of each sill at the bolster is thus doubled, while intermediate the bolster, as the depth of the girder increases, the depth of the reinforcement decreases in approximately the same degree, thereby producing a center sill web, the sectional area of which is constant from the center of the car to its ends, resulting in the formation of a center sill web which, when the parts are prop- 80 85 90 95 100 105 110

erly riveted together, possesses a uniform strength from end to end.

The construction shown in Figs. 1 and 2 is of the type in which draft sills 12 are spliced to the end portions of the center sills, between the bolster and the end sill by means of rivets 13. Ordinarily the center sill webs would be too thin to provide adequate bearing for these rivets, and to compensate for this, it has been customary to supply splice plates, generally of rectangular form within the zone of rivet connection, thus adding metal which is expensive, and weight which it is undesirable to carry. To extend such plates between the bolsters for any considerable distance, would result in unnecessary material between the bolsters. The employment of the piece 11 as indicated, doubles the rivet bearing area used to secure the draft sills in position, and gives the wanted thickness of metal at and near the bolster, without using unnecessary metal at other points.

Fig. 5 illustrates a type of construction in which the center sill web extends to the end sill of a car, and such extension of the center sill web is employed as a draft sill. Ordinarily this construction would result in a weak draft sill or an overstrong center sill between the bolsters, as the thickness of the web is necessarily uniform from end to end, but by utilizing a part cut away, as has been indicated, and as shown in Fig. 1^a, sufficient metal is obtained in the vicinity of the bolsters, without adding any surplus metal between the bolsters.

Another feature of the invention contemplates a peculiar employment of the draft lugs 16, as illustrated. As shown in Figs. 5 and 7, the flange 15 of the draft lug 16 is employed to supplement the bottom chord 5 of the center sill. This chord is riveted directly to the flange 15 and is also connected

thereto through the body portion of the draft lug by means of rivets 20. Thus the flange 15 of the draft lug constitutes a cast metal extension of a structural steel member and eliminates undesirable riveting through the draft lugs, without sacrificing efficiency as would be the case if the angle 50 continued to the end sill, secured only by such rivets as could be conveniently inserted through the draft lug.

What I claim as my invention is:

1. In a car underframe, a fish belly sill comprising a web portion of greater depth near its middle than near its ends and a reinforce plate paralleling and being riveted to said web, said plate being of substantially uniform depth for a portion of its length and of gradually reduced depth for another portion of its length, the reduced portion lapping a portion of the sill web which is of gradually increasing depth.

2. In combination in a car sill, a web portion shallow near its ends and deeper near the middle of its length, in combination with a reinforce plate paralleling said web portion and being of lessening depth near the deeper portion of the web and there secured to said web, and a draft lug secured to said web and plate by through rivets which secure the web and plates together.

3. In combination in a car sill, a web portion deeper at its middle portion than in its end portions, a bottom chord member secured to said web, a draft lug having a bottom flange lapping said bottom chord and being secured thereto, a reinforce plate paralleling said web within the zone of said draft lug and through rivets connecting said web, reinforce plate and draft lug.

In witness whereof I have hereunto set my hand.

PAUL M. BEARD.
